UNITED STATES PATENT OFFICE.

LESTER P. BARLOW, OF PHILADELPHIA, PENNSYLVANIA, ASSIGNOR, BY MESNE
ASSIGNMENTS, TO MARLIN-ROCKWELL CORPORATION, OF NEW YORK, N. Y.,
A CORPORATION OF NEW YORK.

AERIAL EXPLOSIVE DEVICE.

1,325,776.

Specification of Letters Patent. Patented Dec. 23, 1919.

Application filed September 18, 1916. Serial No. 120,604.

To all whom it may concern:

Be it known that I, LESTER P. BARLOW, a citizen of the United States, residing at Philadelphia, in the county of Philadelphia 5 and State of Pennsylvania, have invented certain new and useful Improvements in Aerial Explosive Devices, of which the following is a specification.

My invention relates to aerial explosive devices of the character of what I may term "aerial mortars", that is to say, a construction which comprises a barrel or outer casing which is adapted to be dropped from an aeroplane or other flying machine or projected from a gun; within the barrel or casing is contained an explosive bomb and a device for expelling the bomb from the upper or rear end of the casing after the lower or forward end of the same has struck the earth 20 or other object. The object of such a construction is to provide for the explosion of the bomb after it has been expelled from the casing and therefore above the surface of the earth or other object struck and not, as particularly in the case of striking the earth, within the object struck, with the necessary result of a confined explosion.

My present invention relates to devices of this character, in which the bomb is expelled 30 from the outer casing, after the latter has struck an object and thereby been stopped within a comparatively short distance, by mechanical means, in contra-distinction to the firing of an expelling charge. In the 35 preferred form of my invention, the bomb is slidably mounted within the barrel or casing and rests upon a strong spring which is partly compressed. The bomb is normally prevented from rearward or upward movement in the casing by a detent or locking device, this detent being held in operative position by the upward or rearward pressure of the spring on the bomb. When the forward movement of the casing or barrel is 40 suddenly checked or stopped, the momentum of the bomb carries the same forward compressing the spring to a considerable extent and releasing the locking device. Thereafter, and about the time that the forward 45 movement of the outer casing is entirely stopped within the earth, in my preferred construction, the forward movement of the bomb within the casing is overcome by the 50 force of the charged spring or expelling de-

vice which now acts to expel the bomb from the 55 rear end of the casing. The explosive charge within the bomb is exploded shortly after the bomb has left the casing and preferably at a predetermined distance above the casing. This means for exploding the bomb may become effective after either an interval of 60 space, as by mechanical connection between the bomb and the casing, or after an interval of time, as by means of a delayed charge in the bomb, which may be fired when the bomb 65 starts its upward or rearward movement.

Other objects of my invention consist in the combination of parts and the details of structure more fully described hereinafter and pointed out in the appended claims. 70

In order that a clearer understanding of my invention may be had, attention is hereby directed to the accompanying drawings forming part of this application and illustrating certain embodiments of my invention. In the drawings Figure 1 represents a sectional longitudinal view through a device embodying one form of my invention, Fig. 2 is a similar view showing the device after the outer casing has become embedded 75 in the earth and the bomb has been expelled therefrom and is about to be exploded and Fig. 3 is an enlarged transverse section taken on line 3—3 of Fig. 2.

Referring to the drawings, the outer casing or barrel 1 of the device may comprise a cylinder open at its rear end and provided with stabilizing vanes 2 adjacent the rear end. At its lower or forward end the casing may be closed, but this is not necessary. I 85 prefer to turn the forward edge of the cylindrical casing inwardly to form an annular flange or seat 3. The spiral spring 4 is adapted to be seated upon this flange or seat 3 with the bomb 5 mounted above or to the 90 rear of the spring.

It is highly desirable that the outer casing or barrel should penetrate the earth when the latter is struck, for a comparatively short distance only, so that the forward or 100 downward movement of the same ceases at or before the time that the reverse movement of the bomb begins. The outer casing or barrel should also penetrate the earth vertically or at approximately the same angle at 105 which it struck the same. These objects may be accomplished by keeping the center of gravity well forward in the casing, provid-

ing straight stabilizing vanes, such as those illustrated and providing at the forward end of the casing a device for preventing too great penetration, while permitting a sufficient penetration. In the form of my device illustrated, I have provided a flanged striking member 6 which may comprise an outwardly curved or slightly conical body portion 6' and a plurality of what I term "spreading flanges" 6''. The metal of which the curved body portion 6' is formed may be reversely bent around the periphery thereof and then slotted to form the flanges 6'', the member being welded or otherwise secured to the forward end of the casing 1 adjacent to the base of the body portion 6', as shown at 7. When the forward end of the structure strikes the earth, the flanges 6'' which are bent outwardly somewhat will spread apart to retard the penetration of the casing and prevent the same going too deep.

The bomb 5, or a member 8 upon which the bomb rests, is mounted upon or to the rear of spring 4, the lower or striking end of the casing being referred to as the forward end and the upper or opposite end of the casing referred to as the rear end thereof. The bomb is pressed forwardly against the spring, so that the latter is normally under a certain amount of compression. The bomb is slidably mounted within casing 1, both bomb and casing preferably being cylindrical and the bomb being of sufficient diameter to have a sliding fit in the casing.

To obtain a rapid and effective expulsion of the bomb from the casing, spring 4 should be of considerable stiffness. Also, for the best results, the spring should be sufficiently stressed before the propulsion of the entire device to more than counterbalance the weight of the bomb; that is, in the case of a structure which is to be dropped vertically, the spring should tend to move the bomb upwardly in the casing. Accordingly, I provide a locking or detent device for preventing such upward or rearward movement of the bomb in the casing and maintaining the spring under compression, this detent being adapted to be moved into inoperative position when the forward movement of the outer casing is suddenly stopped or checked and the bomb accordingly moves forwardly against the spring.

A suitable detent is illustrated in the drawings in which it will be seen that casing 1 is longitudinally slotted at opposite points 8', 8''. A cylindrical opening 9 extends transversely through the upper solid portion of bomb 5 and a pair of short sleeve members 10, 10 are slidably mounted in this passage 9. A spiral spring 11 extends through the two members 10, 10, each end of the spring being secured to a pin 12 mounted in the outer end of both of the members 10.

Each member 10 has a notch 13 in its upper

surface which is adapted to engage with the edge 14 of casing 1 constituting the upper wall of each slot 8'. A set-screw 15 extends axially through the upper or rear end of the bomb into the passage 9, to form an abutment against which members 10 strike when they are drawn inwardly by spring 11.

When the device is assembled, spring 4 is compressed by exerting forward pressure thereon through bomb 5, members 10 being pressed outwardly through slots 8' and the bomb then allowed to move rearwardly a sufficient amount to engage notches 13 with the edges 14 of the casing. Members 10 therefore provide a lock or detent preventing the bomb from moving rearwardly or upwardly, while spring 4 normally prevents the bomb from moving forwardly in the casing. Also, the engagement of edges 14 of the casing with notches 13 prevents members 10 moving inwardly. When the casing containing these parts is dropped or projected and strikes an object, the forward movement of the casing is suddenly stopped, or the forward movement of the casing is given a rapid negative acceleration as the casing is brought to rest within the earth. The momentum of the bomb which is of considerable weight carries the same forward or downward compressing or stressing spring 4 to a considerable extent, members 10 moving inwardly as soon as notches 13 thereof have moved away from edges 14 of the casing. Members 10 in their inner or inoperative positions are contained entirely within the periphery of the bomb, so that they offer no resistance to the movement of the bomb in the casing. When the forward momentum of the bomb has been overcome and the spring 4 considerably stressed thereby, the spring reacts to expel the bomb from the casing, as is indicated in Fig. 2. In case the device is dropped upon the earth, the movement of the casing will cease at just about the moment that the forward movement of the bomb in the casing ceases and the expelling movement of the same begins.

In regard to the detent or locking member, it is only essential that the same should contact with the relatively fixed member, namely the casing 1, and one of the members movable therein, such as the bomb to prevent the rearward movement of the bomb, or the unstressing of the spring until the forward end of the casing strikes against an object as stated.

The bomb contains a magazine chamber 15 filled with a high explosive and provision must be made for exploding this substance after the bomb has been expelled from its casing. This may be accomplished in several ways. The method illustrated herein is described and claimed in my co-pending application aerial mortars, Serial No. 117,578, filed August 30, 1916. This consists in con-

necting a movable member of the bomb with the casing by a flexible cable which becomes taut when the bomb has been expelled for a desired distance from the casing. The cable 5 in becoming taut stops the movable member of the bomb and thereby causes a firing pin to contact with a fuse-cap to explode the bomb.

As illustrated, the flexible cable 16 may be 10 connected at its lower end, as shown at 17, to the striking member 6' of the casing, the opposite end of the cable being connected, as shown at 18, to the movable member 8 of the bomb. A screw plug 19 is mounted in the 15 lower end of the bomb, this screw plug having an axial opening extending therethrough. In the upper end of this opening may be mounted the detonator 20 containing a suitable detonating material within the 20 mass of high explosive in the magazine chamber 15. Detonator 20 has a depending annular flange 21 which is secured as by a screw connection within the upper bore of member 19.

25 The member 8 to which cable 16 is secured has an upwardly extending cylindrical portion 22 which is slidably mounted within the lower portion of the bore extending through member 19. A fuse-cap indicated 30 at 23 is secured in the upper end of cylindrical portion 22 of member 8, as by screw-threading the same therein, member 22 being hollow. A bridge piece 24 is secured in the side walls of member 19 and extends 35 diametrically across the opening therein, this bridge piece being provided with a central upwardly extending firing pin 25. The walls of tubular portion 22 of member 8 are vertically slotted to permit relative movement 40 between member 22 and bridge piece 24, bridge piece 24 extending through these slots.

The upper surface of spring 4 presses 45 against the lower surface of member 8. Accordingly, when spring 4 is permitted to expand, after being violently compressed, member 8 is rapidly expelled from the casing with the bomb resting thereon. When cable 16 becomes taut, the upward or rearward movement of member 8 is suddenly arrested, while the momentum of bomb 5 carries the same on. That is to say that the fuse-cap 23 is stopped while the firing pin 25, which is secured to the bomb, continues 50 its movement, striking the fuse-cap which explodes, thereby exploding detonator 20 and the high explosive material contained in magazine chamber 15. The construction of fuse-cap 23 is well known and is not illustrated herein in detail.

It will be observed that the construction described is simple in character, doing away with considerable mechanism which must be employed when the bomb is expelled from 55 the casing by an explosive. The action is

also positive and is of a high degree of certainty in the operation. My invention is not limited strictly to the exact form of construction which has been described in detail herein. The important point of the invention is the utilization of a mechanical or non-explosive device which is to be put in operative condition by the impact of the casing against an object struck, the relative movement between the casing and a body 70 having considerable inertia therein, such as the bomb, being caused to place the expelling device in operative condition; the expelling device thereafter expelling the bomb and the latter being exploded after it has left the 75 casing and preferably after it has left the casing a predetermined distance or a predetermined time.

What I claim is:—

1. In an aerial explosive device, the combination of an elongated casing having a seat at its forward end and open at its rear end, a spring mounted on said seat, a bomb having a bursting charge therein, slidably mounted in said casing, to the rear of, and resting on, said spring, said spring being under partial compression, and detent means normally preventing rearward movement of said bomb in said casing, and so constructed as to be moved into inoperative position 90 by forward movement of said bomb against said spring, said spring being sufficiently strong to normally prevent forward movement of said bomb and to expel said bomb from said casing when strongly compressed, 100 substantially as set forth.

2. In an aerial explosive device, the combination of an elongated casing open at its rear end, a spring mounted in the forward end of said casing, a bomb having a bursting 105 charge therein, slidably mounted in said casing, to the rear of, and resting on, said spring, said spring being partly compressed thereby; detent means normally coacting with said bomb and casing to prevent rearward movement of said bomb in said casing, held in operative position by the upward pressure of said spring, and arranged to be moved into inoperative position when said bomb moves forwardly against the pressure 110 of said spring, said spring being sufficiently strong to normally prevent forward movement of said bomb, and to expel said bomb from said casing when strongly compressed; and means for exploding said bomb after 120 it has been expelled from said casing, substantially as set forth.

3. In an aerial explosive device, the combination of an elongated casing, adapted to be dropped or projected, forward end first; 125 a mechanical expelling device, and an explosive bomb, in said casing, and a locking device, adapted normally to prevent the movement of said bomb from the rear end of the casing; said locking device being ar- 130

ranged to be released by the violent impact of the forward end of said casing against an object, and said expelling device adapted to expel said bomb from the rear end of the casing after such impact and release of said locking device, substantially as set forth.

4. In an aerial explosive device, the combination of an elongated casing, adapted to be dropped or projected, forward end first; 10 resilient means in the forward part of said casing and an explosive bomb to the rear of the same, so arranged that sudden stoppage or rapid negative acceleration of the forward movement of said casing causes said bomb to compress or stress said resilient means until forward movement of said bomb in the casing is overcome, and said resilient means to then expel said bomb from the rear end of the casing, and means for exploding said bomb, after it has been thus expelled, 20 substantially as set forth.

5. In an aerial explosive device, the combination of an elongated casing, adapted to be dropped or projected, forward end first; 25 resilient means in the forward part of said casing and an explosive bomb to the rear of the same, and detent means normally acting on said bomb, in opposition to the pressure of said resilient means, to hold said bomb 30 in position in the casing, said detent means being arranged to be rendered inoperative by sudden stoppage or rapid negative acceleration of the forward movement of said

casing, said bomb being free to compress said resilient means upon such stoppage or 35 negative acceleration, substantially as set forth.

6. In an aerial explosive device, the combination of an elongated casing, adapted to be dropped or projected, forward end first; 40 resilient means in the forward part of said casing and an explosive bomb to the rear of the same, and detent means adapted normally to prevent rearward movement of said bomb in said casing, comprising a member 45 slidably mounted for transverse movement on said bomb, and adapted to extend outwardly into engagement with an abutment on said casing, and spring means tending to withdraw said member inwardly, out 50 of engagement with said abutment; said member having a shoulder on its upper surface with which said abutment normally engages, to prevent such withdrawing movement of said member, and said bomb and 55 member being free to move forwardly, against said resilient means, upon the sudden stoppage or rapid negative acceleration of the forward movement of said casing, substantially as set forth.

This specification signed and witnessed this 15th day of September, 1916.

LESTER P. BARLOW.
